MONOGRAM AFFIXING DEVICE

Israel Otnow, New York, N. Y., assignor to Dur-lacher & Company, Incorporated, New York, N. Y., a corporation of New York

Application March 21, 1941, Serial No. 384,465

1 Claim. (Cl. 219—19)

This invention relates to certain new and useful improvements in heating devices, and relates more particularly to a novel apparatus designed primarily for affixing initials and other monograms to scarfs, handkerchiefs, and the like.

There has been a growing demand for personalized articles such as scarfs having the initials or the full name of the owner inscribed thereon in some fashion, and whereas the usual practice has been for the purchaser to order a specific article and request the initials to be embroidered or otherwise formed thereon after the purchase, such method does not suit modern demands for speed and efficiency. In other words, the purchaser desires to select the article in the store, have the initials affixed thereto in a few seconds, and walk out with the finished article.

By applying a particular type of thermo-plastic cement to the rear surface of a monogram and allowing the same to dry, the monogram may be thereafter placed on the scarf or other article, heat applied, as by an electric iron, and the monogram is instantaneously and permanently secured to the article.

The principal object of the present invention is to provide an improved type of heating apparatus for this particular purpose; thus eliminating the use of electric irons and other similar devices which cause fire hazards when employed by the general run of inexperienced clerks in 5 and 10 cent stores, the apparatus in this respect constituting a complete ironing unit comprising iron and ironing board which will occupy a minimum amount of space.

Another object of the present invention is to provide a novel device of this character which will cause the initial, monogram, or other indicia, to become affixed to the scarf within a few seconds, and which is safe in operation. A further object of the invention is the provision of an improved apparatus wherein the heating element is disposed within a hinged structure having means for supporting the structure in an elevated position when not in use, thus permitting the cooperating base portion to cool between pressing operations.

Yet another object of the invention is the provision of an improved heating device wherein the handle on the hinged heating element is so positioned as to avoid the possibility of the operator suffering the discomfort of overheating the hands during relative continuous operation.

Other objects and advantages of the invention will be hereinafter specifically pointed out or will become apparent as the specification proceeds.

In the drawing:

Fig. 1 is a top plan view of the preferred embodiment of the present invention.

Fig. 2 is a side elevation thereof.

Fig. 3 is a front elevation, partially in section, of the structure shown in Figs. 1 and 2.

Fig. 4 is a broken top plan view showing a modified construction of the pivotal support for the heating element.

10 Figs. 5 and 6 show further details of the modified construction of the device.

The preferred embodiment of the invention comprises a generally rectangular base member 10 which may be formed of wood or any other suitable material, the upper surface of the base being recessed, as shown at 11, to receive a sheet 12 of asbestos or other heat-insulating material, a rectangular metallic plate 13 being positioned above the asbestos sheet and being secured to the base by means of screws 14. In some instances, the heat-insulating layer 12 may be eliminated, although it is normally desirable to provide this sheet for safety purposes.

Inasmuch as a device of this general character is frequently moved from place to place, it is not always expedient to secure the base to a table or other supporting element by screws or the like, and in order to give additional support to the device when it is not so secured the base 10 is 20 preferably extended beyond plate 13 at both ends of the device, as shown at 16 and 17. These extension portions are formed with suitable spaced apertures 18 which may receive screws, bolts, or the like, in case it is desired to secure the device 25 to a table or other working surface.

The heating element or iron 20 includes a base portion 21 comprising a heat transfer surface and being preferably formed from a relatively thick metal casting. On the upper surface of this portion 30 a substantially rectangular housing 22 is secured, the heating coils (not shown) being positioned within such housing. A thermostat or other heat-responsive element 24 is positioned in a suitable aperture in the upper surface of the housing 22, and a sight opening or window 25 is located adjacent to the forward end of such housing. If desired, the upper surface of the housing may be decorated by means of transverse recesses 26 or otherwise. Contact pins 27 are 35 suitably mounted at the rear end of heating element 20.

The device is pivotally mounted by means of a substantially U shaped bracket 28 comprising an elongated base portion 29 and upright portions 50 30 at each end thereof. An elongated metallic

strip 32 forming an arm is secured along each longitudinal edge of the housing 22 by means of screws 33, and at its rear terminal a screw 35 passes through each arm 32, thus pivotally mounting the heating element on the upright portion 30 of supporting bracket 28. Metallic arms 32 are formed with relatively long extension portions 38 at their forward ends, such portions extending beyond the forward extension 16 of base 10, and a handle 39 connects the forward terminals of such strips 32.

In the modified form of the invention shown in Figs. 4, 5 and 6, the bracket 28 is formed as in the preferred embodiment, with the elongated base portion 29 secured to extension portion 17 of base member 10. In this case, however, elongated arm designated as 42 secured to heating element 20 is formed with an elongated aperture 43 instead of the circular aperture of the preferred embodiment. A substantially U shaped support 45 is welded or otherwise secured to the upright portion 30 of bracket 28, the arms 46 of member 45 extending outwardly just beyond the outer surface of strip 42.

Thus it will be seen that the heating element may be moved up and down on its pivotal support during continuous operation, although when not in use the element may be disposed in the raised position shown in Fig. 6 wherein the lower terminals of arms 42 are supported by arms 46 of U shaped supports 45. When the iron is to be lowered the handle is grasped and moved upwardly a sufficient distance to free the lower ends of arm 42 from supports 45, at which time it may be lowered.

Inasmuch as the combined thickness of the scarf and of the initial or other monogram does not vary greatly, no particular adjustment of the heating element or iron relative to base 13 is required. In the event, however, that a relatively thicker material is to be regularly pressed, a strip of metal or other material of predetermined thickness may be inserted between horizontal portion 29 of support 28 and the base.

In the event that the device is to have relatively continuous operation for long periods, it may be desirable to modify the base structure by eliminating the wood base 10 and providing a plurality of spaced horizontal plates formed from sheet

metal, the upper one constituting the work receiving surface, the several plates being supported in their spaced relationship by means of short legs or bushings, such legs extending below the lowermost plate. The passage of air through the intermediate spaces will have a definite cooling effect upon the base structure. The base structure may be otherwise modified to omit the metallic plate entirely, since any other material may be employed for the work receiving surface which may be covered with fabric or not, as desired.

By employing a device of the character described, it will be apparent that no ironing action is required to cause the monogram to become adhesively affixed to the scarf or other object. Moreover, by employing the proper length of time for application of heat all danger of burning the material is eliminated.

What I claim is:

20 In a heating device for securing monograms or the like to articles of fabric, the combination of an elongated base structure, a plate forming a work-receiving surface mounted on the upper surface thereof, a pivoted heating element comprising a flat plate forming a heat transfer surface adapted to be lowered into engagement with the work on the work-receiving surface, a housing mounted on the flat plate and a heating coil positioned within the housing in heat-conducting relation to the flat plate, supporting means for the heating element comprising elongated arms secured along each longitudinal edge of the element and extending beyond the opposite end portions thereof, a handle secured between the arms at one end thereof, the opposite ends of the arms having elongated, longitudinally disposed, apertures therein, a pair of vertical hinge members mounted on the base structure and carrying pivot members passing through the elongated apertures in the arms, and supporting means for receiving the lower terminals of the arms to maintain the pivoted heating element in an upright position when not in use, said means comprising substantially U shaped members carried by the hinge members, the arms being releasable from the U shaped supporting means by upward movement of the heating element.

ISRAEL OTNOW.
